United States Patent Office.

GEORGE NEILSON, OF BOSTON, MASSACHUSETTS.

Letters Patent No. 75,565, dated March 17, 1868.

IMPROVEMENT IN LAMP-BURNERS.

The Schedule referred to in these Letters Patent and making part of the same.

TO WHOM IT MAY CONCERN:

Be it known that I, GEORGE NEILSON, of Boston, in the county of Suffolk, and State of Massachusetts, have invented certain new and useful Improvements in Lamp-Burners; and I hereby declare the following to be a full, clear, and exact description of the same, reference being had to the accompanying drawings.

My invention relates to that class of burners for hydrocarbon fluids in which the base and wick-tube are combined with an elevated deflector, and air-supply cylinder, upon which such deflector is supported. In an application now pending in the United States Patent Office, I have described and claimed a burner of this class. My present invention, the object of which is to produce a simplified form of the same, consists essentially of, first, the combination, with the wick-tube, of a deflector, and an air-supply cylinder for supporting the same, when the said cylinder constitutes at the same time the rest or seat for the lamp-chimney; second, the combination, with the wick-tube and elevated deflector, of a cylinder forming at once the rest for the deflector and the lamp-chimney and supported upon a perforated air-distributing plate or diaphragm mounted upon the wick-tube; third, the combination, with the wick-tube, and the air-distributing plate or diaphragm mounted thereon, of the deflector and combined air-supply cylinder and chimney-rest, when the latter is detachable and removable from the said diaphragm and wick-tube; fourth, the combination, with the air-supply cylinder, when constituting at the same time the chimney-seat or rest, of springs for supporting the chimney in position; fifth, the construction of the air-distributing plate or diaphragm, as hereinafter described.

To enable those skilled in the art to understand and use my invention, I will now proceed to describe the manner in which the same is or may be carried into effect by reference to the accompanying drawings; in which—

Figure 1 is a vertical central section of a burner constructed in accordance with my invention.

Figure 2 is a like section of the base, wick-tube, and air-distributing diaphragm.

Figure 3 is an elevation of the air-supply cylinder and deflector removed from the burner.

a represents the base of the burner, which carries the wick-tube *b* and wick-adjusting pinions *c*. Above the covered base of the burner a perforated plate or air-distributer, *d*, is mounted upon and firmly attached to the wick-tube, and upon this plate is supported a cylinder, *f*, the lower end of which is made flaring, so as to fit over the plate *d*, and to form a bevelled seat for the chimney. The cylinder *f* may be either soldered or riveted to the diaphragm *d*, or it may be connected with the same by means of catches or lugs, *i*, which are attached to the base of the cylinder, and engage with the diaphragm, as shown in the drawings. The latter arrangement has this advantage, that the cylinder may be readily detached and removed from its seat whenever it is desired to take the burner apart for cleansing or other purposes. By turning or revolving the cylinder on its seat until one of the lugs *i* comes opposite an opening, *h*, formed in the edge of the perforated plate *d*, the lug may be disengaged from the plate and the cylinder lifted from the burner. Upon the upper end of the cylinder, and in proper position above the wick-tube, is supported the deflector, hinged as described in my pending application for Letters Patent hereinbefore referred to. The base of the lamp-chimney is supported upon the bevelled seat *m*, formed by the lower flaring end of the air-supply cylinder, and in order to support the chimney, springs *n* are attached to the cylinder, as represented in fig. 1, which bear against the interior of the chimney in the usual manner.

In order to catch the fluid which exudes from the upper end of the wick and runs down the sides of the wick-tube, I form, in that portion of the air-distributing plate *d* immediately surrounding the wick-tube, a cup or cavity, *s*, into which the fluid is received, and thus prevented from spreading over the burner and lamp.

The burner, when the cylinder *f* is made detachable, is composed of two sections or groups of elements, the first consisting of the air-supply and chimney-rest cylinder and the deflector, the second of the diaphragm or air-distributer upon which the cylinder is supported, the wick-tube, and the base. The former group, together with the chimney, can be removed bodily from the burner, whenever the necessity arises, and the whole construction, as well as the combination of the component parts of the burner, is much simplified. The cup can be of course cleaned whenever desired, access being readily had to it after the cylinder and deflector are detached and removed.

Having now described my invention, and the manner in which the same is or may be carried into effect, what I claim, and desire to secure by Letters Patent, is—

1. The combination, with the wick-tube, of a deflector, and an air-supply cylinder for supporting the same, when the said cylinder constitutes at the same time the rest or seat for the lamp-chimney, as herein described.
2. The combination, with the wick-tube and elevated deflector, of a cylinder, forming at once the rest for the deflector and the lamp-chimney, and supported upon a perforated air-distributing plate or diaphragm mounted upon the wick-tube, substantially as herein described.
3. The combination, with the wick-tube and air-distributing plate or diaphragm mounted thereon, of the deflector and combined air-supply cylinder and chimney-rest, when the latter is detachable and removable from the said diaphragm and wick-tube, substantially as herein shown and described.
4. The combination, with the air-supply cylinder, when constituting at the same time the chimney-seat or rest, of springs for supporting the chimney in position, substantially as herein specified.
5. The combination, with the wick-tube, of the air-distributer or diaphragm and the receptacle or cup formed in that part of the said diaphragm immediately surrounding the wick-tube, as and for the purposes herein shown and set forth.

In testimony whereof, I have signed my name to this specification before two subscribing witnesses.

GEORGE NEILSON.
